UNITED STATES PATENT OFFICE.

ARTHUR A. ROESCH, OF BELLEVILLE, ILLINOIS, ASSIGNOR TO ROESCH ENAMEL RANGE CO., OF BELLEVILLE, ILLINOIS, A CORPORATION OF ILLINOIS.

DESIGN FOR A STOVE.

Application filed April 30, 1928. Serial No. 26,519. Term of patent 7 years.

To all whom it may concern:

Be it known that I, ARTHUR A. ROESCH, a citizen of the United States, residing at Belleville, county of St. Clair, State of Illinois, have invented a new, original, and ornamental design for a stove, of which the following is a specification, reference being had to the accompanying drawing, forming part thereof.

The single figure is a perspective front and side elevation of the stove showing my new design.

I claim:

The ornamental design for a stove as shown.

ARTHUR A. ROESCH.
